CLAIM

The ornamental design for a faucet, as shown and described.

DESCRIPTION

FIG. 1 is a right, top, front perspective view of a bidet faucet embodying my new design;

FIG. 2 is a left side elevational view thereof, the right side elevational view being a mirror image of the left side shown;

FIG. 3 is a front elevational view thereof;

FIG. 4 is a rear elevational view thereof;

FIG. 5 is a top plan view thereof;

FIG. 6 is a bottom plan view thereof;

FIG. 7 is a right, top, front perspective view of a second embodiment, the front elevational view and the bottom plan view of the second embodiment being essentially identical to those of the first embodiment;

FIG. 8 is a left side elevational view thereof, the right side elevational view being a mirror image of the left side shown;

FIG. 9 is a rear elevational view thereof; and,

FIG. 10 is a top plan view thereof.

The broken line representations of holes and mounting structures in FIG. 6 are for purposes of illustration only, and form no part of the claimed design.
